(57) **CLAIM**

The ornamental design for an illuminated alphanumeric character display, as shown and described.

DESCRIPTION

FIG. 1 is a front elevational view of an illuminated alphanumeric character display showing my new design;
FIG. 2 is a rear elevational view thereof;
FIG. 3 is a side view, taken from the left side of FIG. 1, the right side view being a mirror image thereof;
FIG. 4 is a top plan view thereof;
FIG. 5 is a bottom plan view thereof; and,
FIG. 6 is a perspective view thereof.
The broken lines in the drawings showing numerals and house siding are for illustrative purposes only and form no part of the claimed design.
